UNITED STATES PATENT OFFICE.

HORACE M. YORK, OF KENNEBUNK, MAINE.

HOLDER FOR TELEPHONE-RECEIVERS.

SPECIFICATION forming part of Letters Patent No. 668,472, dated February 19, 1901.

Application filed April 30, 1900. Serial No. 14,950. (No model.)

To all whom it may concern:

Be it known that I, HORACE MITCHELL YORK, a citizen of the United States, and a resident of Kennebunk, county of York, and State of Maine, have invented certain new and useful Improvements in Holders for Telephone- Receivers, of which the following is a specification, reference being had to the accompanying drawings, forming a part thereof, in which similar characters of reference indicate corresponding parts.

This invention relates to an improved holder for telephone-receivers; and the object thereof is to provide a device of this character which is adapted to hold the receiver in any desired position contiguous to the ear of a person receiving a message without the necessity of holding the receiver in the hands, whereby a person taking telephone-messages can have the use of both hands for the purpose of writing down the said messages.

The device is applicable for attachment either to the telephone-transmitter or to a wall near the telephone. It is adaptable for adjustment to various positions relative to the transmitter, and it is durable, inexpensive, and effective in operation.

The invention will be hereinafter fully described, and specifically set forth in the annexed claims.

In the accompanying drawings, forming part of this specification, Figure 1 is a perspective view of my improved holder, showing the same connected to a telephone-transmitter and supporting a receiver; and Fig. 2 is a similar view showing the device connected to a wall.

In the practice of my invention I employ, primarily, an arched hanger A, which fits over the stem 1 of the telephone-transmitter and is secured in place by means of the thumbscrew B, which is threaded through the side wall a of the said hanger. Swiveled to the hanger A through the upper wall a' thereof is a swinging rod C, which embodies the uprights c , the horizontal extension c' , and the platform c^2 .

Journalized through the platform c^2 is a spindle D, which has a block d secured to its upper end. This block rests upon the platform c^2 and carries a resilient sheet-metal clamp E, which is adapted to clamp and retain a tele-

phone-receiver, as 2, Fig. 1 of the drawings. The clamp E may be turned to any desired angle upon a horizontal plane, and as a means for maintaining the same in position required the spindle D is provided at its lower end with a threaded portion d' , which engages a thumb-nut F, which bears against the lower surface of the platform c^2 of the rod C.

Located at the bottom of the side wall a of the hanger A are projecting guides or lugs a^2 , which engage an upwardly-extended projection g of a rod G, which is adapted to be secured to the wall, as 3, by means of screws 4, which pass through the downwardly-extended plate g' of the rod G. This rod comprises two sections G' and G^2 , which are connected by means of the knife-joint g^4 , whereby by reversing the position of the rod G relative to the hanger C the section G^2 may be maintained in upright position for the purpose of attaching the plate g' to the upper surface of a desk, shelf, or other horizontal projection, as illustrated by dotted lines, Fig. 2, of the drawings.

I do not confine myself to the specific details of mechanical construction as herein shown and described, as it is obvious that under the scope of my invention I am entitled to structural variations. For instance, the clamp E may be connected to the rod C by means of a ball-and-socket or other universal joint, if desired.

The operations and use of the device are obvious. It is connected in the vicinity of the telephone-transmitter in such relative position that the receiver may be placed in the clamp E and carried to the desired position near the ear of the person using the telephone, and the swinging rod C admits of readily placing the device out of the way when it is not in use.

Having thus described my invention, what I claim as new, and desire to secure by Letters Patent, is—

1. In a holder for telephone-receivers, the combination of the hanger A, and means for supporting the same substantially as described, with the rod C, supported at one end by said hanger, and bent as specified, the platform c^2 , on the other end of said rod, the spindle D, passing through said platform, the nut F, engaging a screw on said spindle the

block *d*, upon said spindle, and resting on said platform, and the resilient clamp *E*, surmounting the said block, all substantially as and for the purpose set forth.

5 2. In a holder for telephone-receivers, the combination with the hanger *A*, and means substantially as specified for supporting the same, the screw *B*, working in the said wall of the said hanger, and the rod *C*, bent as set 10 forth, and supported at the end of said hanger, of the platform *c*², upon the free end of said rod, the spindle *D*, passing through said platform, the nut *F*, engaging a screw on said spindle, the block *d*, on said spindle and the 15 resilient clamp *E*, surmounting the said block, all substantially as and for the purpose set forth.

3. In a holder for telephone-receivers, the combination with the hanger *A*, the screw *B*, 20 working in the side wall thereof, the bar *G*, bent at both ends as specified, and composed of two sections *G'* and *G*², the knife-joint *g*⁴

connecting said sections, means of support for the end *g'*, of said bar as described, lugs *a*², on said hanger *A*, embracing the sides of the end *g*, of said bar, while said end *g*, is fastened to the hanger *A*, by said screw *B*; of the platform *c*², the rod *C*, connecting the said hanger *A*, and said platform, the block *d*, surmounting said platform, the screw *D*, 3 integral with said block *d*, and passing downward through said platform, the nut *F*, working upon said screw, and the resilient clamp *E*, resting upon and surmounting the block *d*, all substantially as and for the purpose set 3 forth.

In testimony that I claim the foregoing as my invention I have signed my name, in presence of two witnesses, this 23d day of April, A. D. 1900.

HORACE M. YORK.
